DEVICE FOR DEFINING THE BASE LINES ON
THE HUMAN BODY FOR TAKING THE
MEASURELena von Däniken, Schaffhausen, and Josef
Geisser, Lucerne, SwitzerlandApplication January 11, 1943, Serial No. 472,064
In Switzerland September 11, 1941

1 Claim. (Cl. 33—8)

The present invention relates to a method and a device for taking measures on the human body.

The method which forms one part of the present invention is characterized by the fact that a pillar of a stand which is provided with a scale division is set vertically to touch the upright standing human body in conformity with its middle back line and that the measures to be considered in manufacturing a cutting-model are stated on the body by the interposition of cross bars adapted to be displaced on the pillar and partly provided with scale divisions, arms adapted to be rocked in a horizontal plane and by means of separate auxiliary bars provided with levels and of a scale or a measuring tape.

The device adapted to perform this method comprises a stand in the foot-part of which the lowest element of a pillar is movably inserted, said pillar consisting of members adapted to be screwed one to another, said element being loaded by a spring adapted to be released by foot-pressure, the device comprising further a slide placed on the head of said pillar and adapted to be moved along an element provided with a measure scale, said slide being provided with two vertical guiding rods, an arm being mounted on each of these rods adapted to be displaced along the rod and to be rocked in a horizontal plane, cross-bars being provided between said slide and the foot-part, these cross-bars being partly provided with measure-graduations and one of these cross-bars carrying a cross-level to enable said pillar to be vertically adjusted.

On the accompanying drawings an exemplary embodiment of the device forming a part of the present invention and the manner of employing this device are represented.

Fig. 1 shows the stand with the parts movable thereon.

Figs. 2 and 3 represent the slide in elevation and plan view, partly in section and parts removed.

Fig. 4 is a partial sectional view of the pillar.

Fig. 5 a plan view of a cross-bar, parts being broken away.

Figs. 6 and 7 represent respectively a vertical section according to line *a*—*b* of Fig. 7 and a plan view of the foot-parts, certain parts being broken away.

Figs. 8 and 8*a* are two views of an auxiliary bar and

Figs. 9—11 represent the manner of employing the device on the human body.

On the drawings the numeral 1 represents elements of a stand pillar the lowest of which elements being connected with the foot 3 of the

pillar by means of a Cardan-link 2. A collar 2*a* surrounding the lowest of said elements is rockable around pins 2*b* of the foot 3 and the pillar itself is rockable around pins 2*c* of the collar 2*a*. The cylindrical portion of the foot part 3 is provided with three sockets 4 into which foot-supports 5 are screwed. A foot-pedal 7 is linked to a forked projection 6 on the bottom of the foot-part 3, the stem 8 of a plunger 10 being fastened on said foot-pedal, the plunger being pressed upon by a spring 9 and pressing towards the lower end of the pillar and secures it in its position. Excepting the lowest and the uppermost elements of the pillar which are provided with threaded parts 15 on one side only, all elements of the pillar have on top a threaded bolt 11 and on bottom a corresponding thread-socket 12 (Fig. 4) so that they can easily be built up to form a pillar. The uppermost element 13 of the pillar is provided with a measure-graduation which gives the distance on to the bottom. On this element a slide 14 can be displaced as to height, this slide having two vertical guide-rods 15 which are held together on top by a closed bridle 32 and on bottom by a clamping bridle 33. The measure-graduation on each guide-rod is finer than that on the pillar and each guide-rod is provided with corresponding notches and carries an arm 16 which, by means of a sleeve 17 can be rocked in horizontal direction to a limited extent. The arm 16 extends between ears 18 of the sleeve and has a notch 19 into which reaches a projection 20 of a releasing latch 22, this latch being exposed to the pressure of a spring 21 which with its free end butts against a ring like releasing member 23 adapted to be displaced in horizontal direction and provided with a handle 24 and a nose 25 which lies against the pillar and limits the rocking of the arm. The bore of the releasing member is somewhat greater than the diameter of the rod 15 and has a fine rib 26 which is pressed into a notch of the rod by the spring pressure and prevents the sleeve from being displaced in the height together with the arm. By laterally pressing 45 upon the handle 24 the releasing member is displaced whereby the sleeve becomes free to be displaced. As will be clear from Fig. 3 the angle formed by the maximally rocked arms 16 is less than 180°. By pressing upon the handle of the 50 releasing latch 22 in the direction of the arrow the projection 20 is disengaged from the notch of the arm so that this latter can be rocked upward for easier package. Between the slide 14 and the foot-part 3 two cross bars can be displaced and secured on the pillar by clamping bridles, the

upper one of said cross-bars 27 being the shorter and the lower one, 28, is provided with a measure-graduation on each side of the pillar and carries a cross-level 29.

The cross-level 29 is mounted on a plate 28b forming the upper closing of a clamping socket 28a of the cross-bar 28 and is provided with a level-casing 29a parallel to the bar 28 as well with a level-casing 29b joining to the casing 29a in cross direction.

The device is further provided with two auxiliary bars 30 (Fig. 8) each of which carrying a level 31, a scale for measuring and a measuring-tape will be used for completing the device. All the device can be placed in a portable etui after discomposition to its parts.

For determining the dimensions on a human body the proceeding will be substantially as follows:

The pillar of the stand is set vertically by means of the foot-pedal and the cross-level so as to touch the human body in conformity with the back-line thereof. The lower cross bar 28 is fixed on the level of the seat and the upper cross bar 27 on the level of the shoulder-blade (see Fig. 9). The arms 16 of the slide 14 which serve to measure the shoulders are displaced to the neck projection and the measures are read off on the pillars whereat also unequal a measures are indicated which point to unequal height of the shoulders. Now the arms are rocked away one from another until they are located above the point of the shoulder. The resulting distances between the arms 16 and the points of the shoulders are stated whereat unequal heights of shoulder give also unequal measures (see Fig. 10). Now the other distances are measured which result from the position of the stand-pillar and its cross-bars, with respect to the body. Thereat are to be stated the distances from the pillar to the hind part of the head, to the nape, to the waist and at eventual touching of the upper cross-bar 27 on the shoulder blades there should be stated also the measure up to the seat in order to obtain the

form of the middle back-line seen from the side. Further there are to be measured the distances from the upper cross-bar up to the shoulder-blades and to the haunches and eventual deviations of the back-line from the base-line in the case of unequal shoulders or unequal height of the haunches. For measuring the breadth of the breast and the back the auxiliary bars with the levels are pushed below the shoulder-cavity and the levels adjusted. Hereafter the scale is laid across the bars on the breast or the back respectively and the distance between the bars is read off. For determining the depth of the arm-cavity the measure from the nape over the shoulder up to the upper edge of each auxiliary bar is measured by means of a measuring band and so on.

The measures obtained in this way are inserted into a measure-leaf and according to this normal cutting-pattern is modified.

Instead of a Cardan-link a ball-link could be provided for bearing the pillar.

An exact vertical position of the pillar and exact adjusting of the cross-bars result in exact base-lines and the measures obtained with the aid of the scale-rule and the measuring-band give exact holds for the cut of the pattern also an abnormally grown body so that the dress can be made ready for the customer without trial.

What we claim is:

A measuring device comprising a support, an upright pillar mounted on said support having a graduated scale on the upper part thereof, a slide movable along said pillar and including guide rods disposed substantially parallel to said pillar, arms movable independently in the longitudinal direction and circumferentially of said rods, means for securing said arms in longitudinally adjusted position, means for mounting said arms about horizontal axes whereby they may be swung to inoperative position, and means for locking said arms in horizontal position.
